(57) **CLAIM**

(22) Filed: **Jul. 27, 2004**

The ornamental design for a cylinder housing for air compressor, as shown and described.

Related U.S. Application Data

(63) Continuation-in-part of application No. 10/722,659, filed on Nov. 24, 2003.

DESCRIPTION

(51) **LOC (8) Cl. 15-02**

FIG. 1 is a perspective view of a cylinder housing for air compressor showing my new design;

(52) **U.S. Cl. D15/9**

FIG. 2 is a front elevational view thereof;

(58) **Field of Search** D15/7-9; D23/231,

FIG. 3 is a rear elevational view thereof;

D23/232; 417/410.4, 359, 415, 410.3, 234,
229, 321, 265, 405; 210/220

FIG. 4 is a top plan view thereof;

(56) **References Cited**

FIG. 5 is a bottom plan view thereof;

U.S. PATENT DOCUMENTS

FIG. 6 is a left side elevational view thereof;

4,702,830 A * 10/1987 Makino et al. 210/220
D356,573 S * 3/1995 Makino D15/7

FIG. 7 is a right side elevational view thereof; and,

FIG. 8 is a perspective view thereof, the orifices and pin depicted by means of broken lines being for illustrative purposes only and forming no part of the claimed design.
